UNITED STATES PATENT OFFICE

124,741

DESIGN FOR A COMBINED WASHSTAND AND TOWEL RACK

John H. Irwin, Pittsburgh, Pa.

Application April 17, 1940, Serial No. 91,733

Term of patent 7 years

To all whom it may concern:

Be it known that I, John H. Irwin, a citizen of the United States, residing at Pittsburgh, in the county of Allegheny and State of Pennsylvania, have invented a new, original, and ornamental Design for a Combined Washstand and Towel Rack, of which the following is a specification, reference being had to the accompanying drawing, forming part thereof.

I claim:

The ornamental design for a combined washstand and towel rack, as shown.

JOHN H. IRWIN.
